(57) **CLAIM**

The ornamental design for a ground anchor handle, as shown and described.

DESCRIPTION

FIG. 1 is a top isometric view of a ground anchor handle;

FIG. 2 is a front side view thereof;

FIG. 3 is a back side view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the ground anchor handle that form no part of the claimed design.
